RELEASE FOR HAIR CURLERS

Tomlinson I. Moseley, San Francisco, Calif.

Application November 29, 1935, Serial No. 52,129

2 Claims. (Cl. 132—33)

This invention relates to a hair waving device, and particularly to a clutch for releasing the tension on the spool or shaft on which the hair to be curled is wound.

5 An object of the invention is to provide a hair curling device wherein the hair is wound on a spool or shaft and thereby placed under tension, said spool or shaft having a clutch therein for preventing the spool or shaft from rotating 10 and thereby allowing the hair to unwind, means being provided to release the clutch, and to thereby release the tension on the wound hair, whereby the hair curling device may be quickly and easily removed.

15 Other objects and advantages are to provide a release for hair curlers that will be superior in point of simplicity, inexpensiveness of construction, positiveness of operation, and facility and convenience in use and general efficiency.

20 In this specification and the annexed drawing, the invention is illustrated in the form considered to be the best, but it is to be understood that the invention is not limited to such form, because it may be embodied in other forms; and 25 it is also to be understood that in and by the claims following the description, it is desired to cover the invention in whatsoever form it may be embodied.

In the accompanying drawing:

30 Fig. 1 is a plan view of a conventional form of hair waving device.

Fig. 2 is a side elevation of Fig. 1.

Fig. 3 is an end elevation of Fig. 2.

35 Fig. 4 is an enlarged longitudinal section taken thru an end of the hair curling device, showing a release mechanism constructed in accordance with my invention.

Fig. 5 is a cross section taken thru Fig. 4, on the line 5—5.

40 Fig. 6 is an end view partly in section, taken on the line 6—6 of Fig. 4.

In detail the construction illustrated in the drawing comprises a conventional form of hair holder and curler consisting of plates 8—8 having a pair of complementary base members 1 and 2 arranged on the under side thereof. The base members 1 and 2 are permanently attached to the under side of the respective plates 8, while the plates 8—8 at one end thereof are pivotally 45 connected by a bar 3, whereby the member 2 may be swung apart from the member 1. At the other end of the plate 8 on the member 1, I have provided one form of a clamp for locking the base member 2 in parallelism with the member 1, said clamp consisting of a bar 5 pivoted

at 6 to the under side of the plate 8, the other end of said bar having a cam 7 thereon adapted to be frictionally engaged with the side of the base member 2, for holding it in proper position relative to the base member 1.

5 The matching faces 4—4 of the members 1 and 2 are provided with material or surfacing thereon capable of holding a strand of hair in a non-sliding position.

Standards or brackets 9—9 are provided on 10 the upper surface of the base member 1 at each of the opposite ends thereof, which standards project over and lie above the base member 2, when it is locked in the closed position. Each standard 9 is provided with a vertically disposed 15 slot 10 therein.

A spool or mandrel 11 on which the hair to be curled is wound, is adapted to be rotatably confined in the opposite guide slots 10 of the standards 9—9. The spool or mandrel 11, at one end 20 thereof, is provided with a circular shaft 12, which shaft is rotatably journaled in one of the standards 9. The other end of the spool 11 is provided with a dual diameter bore 13 therein. A circular bushing 14 is rotatably mounted in 25 the larger diameter portion of the bore 12, the outer end of said bushing 14 having a flat sided head 15 thereon, to rest in the slot 10 in the other standard 9.

A spring wire snap ring 16 rests in complementary slots formed respectively in the inner circumference of the bore 13 and the outer circumference of the bushing 14, to prevent axial displacement of the bushing relative to the spool.

30 A coil spring 17 is arranged within the smaller 35 diameter portion of the bore 13, and said spring extends partway within the bushing 14. The spring 17 is wound relatively tight, so that one end thereof bears against the base 18 of the bore 13, while the other end of said spring 40 bears against the base 19 in the bushing 14. The end 20 of the spring 17 within the bushing 14 is bent across the diameter thereof, as shown in Fig. 5.

45 The bushing 14 is drilled out on its longitudinal axis to receive a shaft 21, the inner end of said shaft being slotted to engage the diametrically disposed end 20 of the spring 17. A snap ring 22 is interposed between the bushing 14 and the shaft 21 to permit rotative movement of said 50 shaft but to prevent axial movement thereof.

A knurled handle 23 is provided on the end of the shaft 21 to rotate said shaft and spring, as will be hereinafter described.

55 In the operation of imparting a wave or curl

to the hair, a strand of hair is clamped between the members 1 and 2 at a point adjacent the scalp, whereby the hair which projects thru the 5 holders 1 and 2 may be wound upon the spool or mandrel 1. In winding the hair on the spool or mandrel, the same is removed from the holder and the extreme ends of the hair are held on the spool, in some conventional manner, and the operator rotates the spool with the 10 hair confined thereon toward the scalp until the entire strand has been wound thereon. As the spool, with the hair thereon, reaches the holder, the operator places the same into the slots 10 on the opposite standards 9, and there- 15 after continues to rotate the spool by movement applied thereto, thru the end extension 12, until such time as the wound hair has been placed under the desired degree of tension. It will be noted that the spool 11 rotates about the bush- 20 ing 14, the squared end of said bushing preventing it from turning in the standard. The end of the spring 17 bears against the base 18 of the bore 13 so that the spool may be rotated in one direction to wind the hair on the spool, 25 but may not move in the opposite direction. The contact or engagement between the end of the spring 17 and the base 18 of the bore 13 is such that the end of the spring expands into frictional contact therewith, and thereby prevents 30 such rotative movement of the spool 11 as would permit the hair to unwind or become loosened. When hair is tightly wound on the spool 11, it exerts a force directly against the spring, and tends to unwind it, but due to the close wrap 35 of the spring, the spring cannot give, and as a result, the spool is held immovable.

The spring 17 in its relation to the spool 11, is that of a one-way clutch. When the hair is wound tightly on the spool, the spring 17 is 40 placed under tension sufficient to prevent the spool from turning. Upon completion of the hair waving operation, or if for any other reason it should be desired to release hair wound on the spool, the operator merely rotates the shaft 21, 45 to declutch or disconnect the spring 17 from the spool, whereby the tension on the wound hair is released, and the spool may be removed from the standards. When the hair is wound on the spool, the said spool rotates in a clockwise direc-

tion relative to the end of the spring, and when it is desired to release the connection between the spring and the spool, the spring is rotated in a counter-clockwise direction by the shaft 21.

I have found that by embodying a release 5 mechanism of the kind heretofore described, in a hair curler, that it is possible to release the curlers from the hair with absolutely no discom- 10 fiture to the patient. The usual type of hair curler is not provided with any means for re- 15 leasing the tension on the hair curler, other than by opening up the members which clamp the hair adjacent the scalp, and then manipulating the holder into an inverted position so that the spool may be discharged or released therefrom. 20 This procedure usually causes the patient a great deal of discomfort, and where the head is blocked out with a number of hair holders and curlers throughout the entire area thereof, it is exceedingly difficult to release the hair from 25 the curlers. With my release mechanism, tension on the hair can be released quickly and easily, and the hair curling apparatus can be removed from the head without hurting the patient in the slightest degree.

Having thus described this invention, what I claim and desire to secure by Letters Patent is:

1. A release for hair curlers, comprising a base having slotted standards at its opposite ends; a spool, on which hair to be curled is wound, having a shaft fixed to the spool at one end and a shaft on which the spool is journaled at its other end, said end shafts being demountably confined in the opposite slotted standards; a spring clutch arranged in the spool adjacent the shaft on which the spool is journaled permitting one way rota- 30 tion of the spool to wind hair thereon; and means operable thru the last mentioned shaft to release the clutch from the spool to permit removal of the spool and unwinding of the hair.

2. A hair curling device, comprising in combination, a hair clamp, a hair curler demountably journaled on the clamp; a spring clutch located within the curler on the axis of rotation thereof and related to the clamp to permit one way rota- 45 tion only of the curler; and means to release the spring clutch to permit rotation of the curler in either direction.

TOMLINSON I. MOSELEY.
